ELEVATOR

George O. Wright, Kilgore, Tex., assignor of one-third to A. P. Merritt and one-third to L. E. Brown, Gregg County, Tex.

Application November 8, 1937, Serial No. 173,418

4 Claims. (Cl. 294—103)

This invention relates to an elevator.

An object of the invention is to provide a device of the character described specially designed for elevating, gripping and holding or turning, round objects as sections of pipe.

One of the objects of the invention is to provide an elevator of the character described which may be readily applied to a section of pipe for elevating the same and for lowering the section being handled into the rat hole adjacent a well drilling rig.

It is another object of the invention to provide apparatus of the character described whereby the section of pipe in the rat hole may be gripped and held against turning while an additional section, such as a grief joint, is being screwed into the coupling at the upper end of the section so being held.

It is another object of the invention to provide a pipe handling appliance of the character described which will engage, grip, and hold pipe sections of different diameters.

It is a further object of the invention to provide, in a pipe handling apparatus of this character, a novel type of pipe gripping jaw.

The invention also comprehends the combination of a novel type of elevator and a novel type of rat hole casing whereby the attachment of the grief joint to the section in the rat hole may be facilitated.

With the above and other objects in view the invention has particular relation to certain novel features of construction, operation and arrangement of parts, an example of which is given in this specification and illustrated in the accompanying drawings, wherein:

Figure 1 shows a plan view of the elevator.

Figure 2 shows a sectional view taken on the line 2—2 of Figure 1.

Figure 3 shows a sectional view of the elevator body taken on the line 3—3 of Figure 1.

Figure 4 shows a fragmentary, sectional view of the upper end of the rat hole casing, and

Figure 5 shows a fragmentary, side view of a well drilling rig showing the elevator mounted on the rat hole casing, said casing being shown in section.

Referring now more particularly to the drawings wherein like numerals of reference designate the same parts in each of the figures, the numeral 1 designates the elevator body which is approximately circular and whose upper end has the outwardly extending flange 2. At one side the elevator body has a deep slot 3 and is provided with the outwardly extended parallel lugs 4, 4

on opposite sides of said slot, said lugs forming anchors for the transverse pin 5.

On opposite sides of the slot 3 the body is slightly elevated or thickened vertically and has the downwardly and inwardly tapering faces 6, 6. 5 Opposite the slot 3 and countersunk into the inside of the body 1 and the top of the flange 2 there is a stationary pipe gripping jaw 7 having the inside toothed arcuate face 8. This jaw is secured to the flange 2 by a suitable set bolt 9. 10

There is a lifting lever 10 between the lugs 4 and extended through the slot 3. This lever has the upstanding grip 11 thereon and its outer end is formed into an eye 12 for the attachment thereto of a cable 16 which operates over the 15 crown block (not shown) of the derrick and is operated from the cat head 17.

The inner end of the lever 10 is extended laterally each way forming a head 18 which has the tapering faces 19 to coact with the tapering 20 faces 6. This head has the diverging prongs 20, 20 forming guides for centering a pipe section as 21 therein. The forward, or inner side of the head has the cylindrical sockets 22, 22 extending downwardly from the upper side of the head 25 but not extending entirely through the head. Pipe grips 23, 23 are in these sockets. These grips have approximately cylindrical tenons 24, 24 which conform in shape to and are fitted in the cylindrical sockets 22 to freely turn about 30 their axes. These tenons are retained in place by a cross-strap 25 which abuts their upper ends and which is secured to the head by the set bolts as 26. The grips project forwardly from the head and are formed with the flared gripping 35 jaws 27 whose outer margins are serrated having the grip teeth 28. The points of these teeth lie approximately in planes which are at right angles to the radial lines of the respective tenons 24. 40

The sections of the drill stem, or other pipe to be lowered into a well, are usually located in approximately horizontal position on a pipe rack adjacent the derrick. These sections may be swung, one at a time, by the elevator and lowered into the rat hole 29 having the rat hole casing 30 therein. The upper end of this casing 30 has a wide notch 31 therein, said notch being somewhat wider than the overall width of the lugs 4 for a reason to be hereinafter stated. 45

When it is desired to locate a section as 21, of the pipe in the rat hole, in readiness for the attachment of the grief joint thereto, the elevator may be swung over to the pipe rack and passed over the tool joint box member, or coupling, 32 50 55

on the upper end of said section. The lever 10 should be swung around, on the pin 5 to carry the head 18 out of the way of said coupling to permit the body 1 to be passed over the coupling 5 and said lever may then be swung back into the position shown in Figure 2 to carry the head back into the body as shown in Figure 2 with the grips 23 in engagement with the pipe section 21. When so swung back into said position the head will 10 move inwardly, the sloping faces 19 riding downwardly against the inwardly declining, sloping faces 6 until the pipe is securely gripped between the grip 7 and the grips 23. To permit this freedom of movement of the head 18 the opening 33 15 through the lever 10 which receives the pin 5 is somewhat larger than said pin as is clearly shown in Figure 2. The elevator and section of pipe engaged thereby may then be elevated by the cat line, or cable, 16 in the usual way and swung over 20 and the pipe section lowered into the rat hole. The body 1 will enter the upper end of the casing 30 and the lugs 4, 4, will enter the slot 31 and the elevator flange 2 will land on the top of the casing 30.

When, in the process of drilling, an additional section must be added to the upper end of the drill pipe 34 in the well, the grief joint (not shown) may be broken out, or unscrewed, from the drill pipe 34 and swung over and its lower end 30 screwed into the tool joint member 32 by appliances commonly used about a well drilling rig for that purpose.

As the grief pipe is screwed into the box member 32 the jaw 7 and the grips 23 will securely grip 35 and hold the section 21 against turning, the tenons 24 pivoting about their axes. As the tenons pivot it is obvious that the outer teeth 28 of one jaw 27 and the inner teeth 28 of the other jaw 27 will move slightly inwardly toward the axis of the 40 body 1 securely gripping the section 21 to hold it against turning. This movement of the gripping jaws 27 and the inward range of movement of the head 18, above referred to, permits pipes or other round objects of varying diameters to be securely gripped and held by the elevator.

When the grief joint has been connected to the drill stem section 21 the joint and section may be elevated and swung over the drill stem 34 and attached thereto and the drill stem then lowered 50 until the grief joint is in position to be engaged by the conventional bushing of the rotary table 35 and drilling proceeded with.

It sometimes happens that the threads of the grief joint cannot be screwed fully home in the 55 tool joint box member 32 by the ordinary method. In such a case the handle 10 of the elevator may be pulled around to the left until one of the lugs 4 engages the opposing side of the slot 31 and a sudden torsional stress may be then imparted to 60 the grief joint causing the section 21 and the elevator to suddenly turn until the other lug 4 strikes the opposite side of the slot 31 and this

may be repeated if necessary until the jar, or repeated jars, cause the threads to fully make up.

The elevator may be used for holding one section of pipe while unscrewing another section therefrom in which event the grips 23 will operate 5 in the reverse manner to that hereinabove described.

The drawings and description disclose what is now considered to be a preferred form of the invention by way of illustration only, while the 10 broad principle of the invention will be defined by the appended claims.

What I claim is:-

1. An elevator comprising a body having an opening therethrough and having an inside tapering bearing face, fixed engaging means at one side of the opening, a carrier pivotally mounted on the head and having a downwardly and inwardly tapering bearing face, said carrier being movable into active and inactive positions and the bearing 15 faces being arranged to co-act when the carrier is in said active position and engaging means on the carrier.

2. An elevator comprising an annular body having an opening therethrough to receive a pipe, 25 a pipe engaging jaw on one side of the body, said body having a slot opposite the jaw and downwardly and inwardly inside tapering faces on the opposite sides of the slot, outwardly extended lugs on opposite sides of the slot, a lever pivotally 30 mounted between the lugs, a head on the inner end of the lever forming a carrier, said head having tapering faces which co-act with the faces of the carrier and having inwardly extended guide prongs and pivotally mounted pipe engaging 35 means on the carrier between the prongs.

3. An elevator comprising an approximately annular body having a slot at one side and outwardly extended lugs on opposite sides of the slot, a pipe engaging jaw in the body opposite the slot, 40 a lever extended through the slot and loosely pivoted between the lugs, a head on the inner end of the lever forming a carrier, said head and body having cooperating downwardly and inwardly tapering faces, a plurality of pipe engaging jaws 45 on the carrier opposite the fixed jaw.

4. An elevator comprising an approximately circular body having an opening therethrough to receive a pipe to be elevated, said body having a side slot and having inside, downwardly and inwardly tapering faces on opposite sides of the slot, 50 outwardly extended lugs on opposite sides of the slot, a lever pivotally mounted between the lugs, said lever being mounted loosely to permit a radial movement thereof relative to the axis of its 55 pivotal mounting, a head on the inner end of the lever forming a carrier and having tapering faces which co-act with the faces of the body to cause the head to wedge tightly against the pipe upon upward movement of the elevator.

GEORGE O. WRIGHT.
